CLEANERS FOR RAILROAD CAR WHEELS AND BEARINGS

John A. Schroeder and Kenneth J. Glasmann, Denver,
Colo., assignors to Paxton Mitchell Co., Omaha, Nebr.
Application January 25, 1954, Serial No. 406,026
7 Claims. (Cl. 134—123)

This invention relates to a device for cleaning railway car wheels, journals, and bearings, and is more particularly applicable to wheels having anti-friction bearings of the ball and roller types.

The principal object of the invention is to provide, in a single, unitary device, means whereby the wheels, journals and the bearings and bearing boxes for the journals will be simultaneously cleaned and to so construct the device that the wheels may be rolled therein on a conventional track without it being necessary to lift, hoist or handle the wheels.

Another object of the invention is to provide an adjustable spray support for directing a plurality of cleaning sprays against the wheels and journals which will be quickly and easily adjustable to accommodate wheels of various types and sizes.

A further object is to provide rotary spray tables for receiving the bearings and bearing boxes of the wheels being cleaned which will operate simultaneously with the wheel cleaning mechanism to efficiently and perfectly clean the boxes and the anti-friction type bearings therein and which assure each box being returned to the same journal from which it was removed.

A still further object is to provide means for ejecting the cleaned wheels from the device after the cleaning operation has been completed.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a plan view of the improved car wheel and bearing cleaning device;

Fig. 2 is a front view thereof, illustrating it in the open position, with a conventional car wheel assembly in place therein;

Fig. 3 is an enlarged, fragmentary, vertical section, taken on the line 3—3, Fig. 4, with a wheel assembly in place therein;

Fig. 4 is a similarly enlarged, fragmentary horizontal section, taken on the line 4—4, Fig. 3, with the wheel assembly removed;

Fig. 5 is a still further enlarged cross-section, taken on the line 5—5, Fig. 4; and

Fig. 6 is an enlarged detail section, taken on the line 6—6, Fig. 4.

In the drawing a conventional car wheel axle is indicated at 10, with its wheels at 11 and wheel journals at 12.

The improved cleaning device employs a pair of horizontal, parallel, wheel-supporting shafts 13 and 14 mounted in suitable supporting bearings 15. Each of the shafts 13 and 14 carries a pair of fixedly mounted wheel supporting rollers 16, the rollers on each shaft being spaced apart the standard railway track gauge distance and being in alignment with the rollers in the other shaft. A pair of incoming track rails 17 terminate adjacent the 70 rollers 16 on the shaft 14, and a similar pair of outgoing track rails 18 extend from the rollers 16 on the shaft 13.

2

It can be seen that if an axle 10 with its wheels 11 is rolled on the rails 17 toward the rollers 16, it will come to rest between the rollers on the two shafts, and if these rollers are rotated, the wheels 11 will be simultaneously rotated. The shafts are rotated from any suitable outside power device connected to the projecting extremity of the shaft 13. The shaft 14 is rotated from the shaft 13 through the medium of suitable chain sprockets 19 and an endless transmission chain 20 extending between the shafts about the sprockets.

To remove the wheels from between the rollers 16, lifting levers 21 are provided. The lifting levers are preferably formed from angle irons and are hingedly connected to the extremities of the outgoing rails 18 by means of a suitable hinge bolt 22 with the horizontal legs of the angle irons positioned beneath the rims of the wheels 11. Tread projections 23 are formed on horizontal legs of the lifting levers so as to extend between the pairs of adjacent rollers 16.

The lifting levers 21 extend alongside the incoming rails 17 and rest upon lifting cams 24 mounted on a transverse cam shaft 25. The cam shaft 25 is rotatably mounted in suitable supporting bearings 26 and may be rotated, to cause the cams 24 to lift the levers 21, by means of a hydraulic cylinder 27. The cylinder 27 actuates a hydraulic plunger 28 connecting to an actuating lever 29 fixedly mounted on the extremity of the cam shaft 25.

When it is desired to discharge the wheels 11 from the rollers 16, fluid under pressure is admitted to the cylinder 27 to actuate the cam shaft 25 so as to cause the cams 24 to lift the levers 21 against the rims of the wheels 11 so as to lift the latter above the rollers 16 and allow them to roll down the incline of the lifting levers onto the outgoing rails 18 and from the device.

The wheels being cleaned are enclosed within a wheel housing 30 of sufficient size to receive the largest expected wheels. The wheel housing 30 is permanently closed at its extremities and over its top. The front and back of the wheel housing are closed by means of vertically rising doors 31 which travel in vertical slotted, door guide bars 32 secured to the housing 30 and extending thereabove. Each of the doors is provided with a projecting ear 33 from which a suspension cable 34 extends upwardly over a guide pulley 35 and terminates in a cross head 36. The cross heads 36 are mounted upon hydraulic plungers 37 and are slidable on horizontal guide bars 38. The plungers 37 extend from horizontal hydraulic cylinders 39 supported between the door guide bars 32 upon suitable brackets 40.

It can be seen that if hydraulic fluid is admitted to the cylinders 39 from any suitable source through conduits, such as indicated at 41, the plungers 37 will be projected to draw upon the cables 34 to lift the two doors 31 to the open position of Fig. 2. When the hydraulic fluid is released the doors will return by gravity to the closed position of Fig. 5.

The wheels 11 and their journals are sprayed with suitable detergent and cleaning solutions from a plurality of spray nozzles 42 and 43. The spray nozzles 42 are mounted on vertically adjustable nozzle plates 44 there being one nozzle plate mounted opposite the outside face of each of the wheels 11 and inside the housing 30. The nozzle plates 44 are slidably supported in vertical nozzle plate guides 45 and can be raised and lowered to any desired vertical position in the guides through the medium of foot operated levers 46. One of the levers 46 is mounted below each of the nozzle plates 44 on a pivot 47 supported in a bracket 48 extending from one of the guides 45. Each foot lever is provided with a foot rest 49 at one extremity and with a lifting pad 50 at its other extremity, which bears against the bottom of the nozzle plate 44.

3

Each nozzle plate is supported at any desired height in its guides by means of a locking pin 51 which extends into any desired pin opening in a vertically spaced series of pin openings 52 formed in the plate 44. The purpose of the vertical adjustment of the nozzle plates 44 is to axially align the latter with the wheel axle 10 on car wheels of various diameters.

The spray nozzles 42 are fixedly mounted in the nozzle plates 44 at equally spaced intervals around the periphery thereof. The spray nozzles 43, however, are radially adjustable on the nozzle plates. Each of the nozzles 43 is mounted in the extremity of a nozzle lever 53, each of which is pivoted, as shown at 54, on the adjacent plate 44 so as to swing in an arc parallel to the plane of the latter. The nozzles 43 extend outwardly through arcuate slots 55 formed in the plate 44. Each slot is concentric about the axis of the adjacent pivot member 54 so that each of the nozzles 43 may be swung inwardly and outwardly toward the axis of the plate 44. Cleaning fluid is fed under pressure to the nozzles 42 and 43 through a plurality of fluid hoses 63 leading from fluid manifolds 64.

The adjustment of the nozzles 43 is accomplished through the medium of a multiple armed rotary member 56 mounted to rotate about an axis bolt 57 concentrically positioned in each plate 44. Each arm of each of the members 56 terminates in a stud 58, and each stud rides in an elongated slot 59 in one of the nozzle levers 43. The member 56 is rotated from a hand lever 60 which is formed as an extension of one of the arms of the member 56. The hand lever 60 can be locked in any desired angular position by means of a locking pin 61 which can be interfitted into any one of a plurality of locking holes 62 in the plate 44. It can be seen that with cleaning fluid flowing through the nozzles 42, the lever 60 can be actuated to swing the nozzles 43 inwardly and outwardly to clean the entire wheel and journal surface.

As each wheel and axle assembly is prepared for entering the cleaning housing, the bearing boxes are removed from the journals and placed on rotary tables 65 as indicated in broken line at 77 in Fig. 3. There is one rotary table at each extremity of the housing 30 to receive the two boxes of the wheel and axle assembly being cleaned. This maintains each box opposite the journal from which it was removed so that each box can be re-placed upon its respective journal without interchange.

The rotary tables 65 are driven from pin wheels 66, the pins of which enter notches 67 in the tables. The pin wheels are simply one means of driving the tables. They could be driven by bevel gears or the like. One of the pin wheels 66 is fixedly mounted on each extremity of the wheel shaft 14. The tables 65 are rotatably mounted about hollow vertical standards 68 upon thrust bearings 79 supported on supporting sleeves 80 resting upon supporting bases 81.

A fluid pipe 69 extends upwardly through the standard 68 above the table and supports a whirling spray nozzle 70 upon a suitable ball bearing 78. The nozzle is provided with two downwardly extending tubes provided with spray perforations 82 positioned so that the reaction of the jets will whirl the nozzle. A stepped base 71 is mounted concentrically of the tables 65, and the steps are designed to interfit into bearing boxes of various diameters.

The tables 65 are mounted in table housings 72 at each extremity of the wheel housing 30. Access may be had to the table housings 72 through the medium of hinged lids 73 provided with hand lifts 74. The lids 73 can be latched in the open position by means of studs 75 secured to the lids and positioned to be engaged by latch hooks 76 mounted on the door guides 32.

It is believed that the operation of the device will be clear from the above description. Briefly, a wheel and axle assembly is rolled up to the device on the incoming rails 17. The two bearing boxes 77 are removed from

the journals 12 and placed on the two tables 65. The wheels are then rolled into the housing 30 onto the rollers 16 and the doors 31 are lowered.

Rotation of the shaft 13 is started and cleaning solution, preferably hot, is pumped to the manifold 64 and the fluid pipes 69. The nozzles 42 and 43 spray cleaning solution upon the wheels and journals while the jets from the whirling nozzles 70 thoroughly wash the bearings and the bearing boxes.

The rotation and solution flow is then stopped and hydraulic fluid is admitted to the cylinders 39 to open the doors and to the cylinder 27 to roll the cleaned wheels onto the outgoing track rails 18 and from the device. The bearing boxes are now removed from the tables and replaced on their journals, and the job is completed.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A device for cleaning the journals and bearings of a railway wheel and axle assembly comprising: spaced-apart wheel-receiving rollers adapted to receive the wheels of said assembly; a nozzle-supporting member positioned at each extremity of said wheel and axle assembly; nozzles mounted in each nozzle-supporting member; means for projecting cleaning fluid through said nozzles against said assembly; and means for rotating said rollers.

2. A device for cleaning the journals and bearings of a railway wheel and axle assembly as described in claim 1 having means for varying the positions of said nozzles transversely of the axis of said wheel and axle assembly.

3. A device for cleaning the journals and bearings of a railway wheel and axle assembly as described in claim 2 in which the means for varying comprises: a nozzle-supporting plate positioned at each extremity of said wheel and axle assembly; vertical nozzle plate guides supporting each plate, said plates being vertically movable in said guides; and means for supporting said plates at any desired height in said guides.

4. A device for cleaning the journals and bearings of a railway wheel and axle assembly as described in claim 3 having means for varying the radial position of certain of said nozzles on each of said nozzle plates.

5. A device for cleaning the journals and bearings of a railway wheel and axle assembly as described in claim 4 in which the means for varying the radial position of certain of said nozzles comprises: levers pivotally mounted on said nozzle plates so as to swing in a plane parallel to said plates; certain of said nozzles being mounted in the extremities of said levers; and means for swinging said nozzle levers.

6. A device for cleaning the journals and bearings of a railway wheel and axle assembly comprising: spaced-apart wheel-receiving rollers adapted to receive the wheels of said assembly; a nozzle-supporting member positioned at each extremity of said wheel and axle assembly; nozzles mounted in each nozzle-supporting member; means for projecting cleaning fluid through said nozzles against said assembly; and means for rotating said rollers, having incoming rails terminating adjacent said rollers; outgoing rails initiating adjacent said rollers; and hinged lever means extending between the extremities of the incoming and outgoing rails for lifting the wheels therebetween.

7. A device for cleaning the journals and bearings of a railway wheel and axle assembly as described in claim 6 having a cam shaft extending transversely of said rails; a cam on said shaft below each of said wheel levers; and means for rotating said cam shaft to cause said cams to simultaneously contact and lift said wheel levers.
